UNITED STATES PATENT OFFICE.

EMIL ELSAESSER, OF BARMEN-LANGERFELD, AND WALDEMAR ZUR LÖWEN, OF BARMEN-RITTERSHAUSEN, GERMANY, ASSIGNEES, BY MESNE ASSIGNMENTS, TO AMERICAN BEMBERG CORPORATION, A CORPORATION OF DELAWARE.

YARN REEL OR WINDER.

Application filed October 29, 1923, Serial No. 671,564, and in Germany September 8, 1923.

Our invention relates to improvements in yarn reels or winders comprising a rotatable shaft a stationary member and a movable member especially used in winding up artificial threads such as imitation silk yarns and more particularly our invention relates to the means for locking the said movable member with relation to the stated stationary member.

10 Yarn reels especially adapted for use in winding imitation silk usually consist of a rotary shaft having rigidly affixed thereto a pair of crossed or spider-like members or radial arms interconnected at their outer 15 ends by longitudinal bars or rods which are located parallel to each other and to the axis of the shaft so as to form the aforesaid stationary member, that is to say, stationary relatively to the shaft, but adapted to rotate therewith, the reel further comprising a system of similar crossed arms loosely mounted on the shaft to be rockable thereon relatively to the stationary member, and having their outer ends likewise connected by parallel bars or rods.

As is known to those skilled in the art the purpose of the displaceable system of interconnected arms is to have a means for removing the wound up skein or skeins of yarn 30 from the reel. In reels of the kind hitherto employed the angularly displaceable system of arms and winding bars is usually locked in its operative position by means of locking pins in co-operation with an abutment 35 adapted to arrest the system in its operative position. Upon removal of the pin or pins the system can be turned about the shaft as far as required for removing the skeins and thereafter can be turned back, until it will 40 be stopped by the mentioned abutment and can be fixed by the said pin or pins in its operative position for the next winding operation.

The object of our invention is to provide 45 a more reliable and efficient means for arresting and locking the movable system or arms in their operative position. With this object in view we provide a single spring arresting and locking device in lieu of the hitherto employed two contrivances and as 50 far as our knowledge goes, springs or any other yielding locking means have never been used heretofore and are broadly new in connection with yarn reels of the kind set forth.

In accordance with our invention the stopping and locking device comprises a spring 55 made of acid-proof material and of a particular shape adapted to ensure the double result of locking the movable system in its operative position and at the same time acting as a means for limiting the rotary movement of the system. To this end the spring is given a double bend to form a seat for a locking lug or nose to engage therein, and is further bent outwards to provide a stop 60 which the said nose cannot overcome when catching or engaging into the seat.

In the accompanying drawing a single embodiment of our invention is illustrated by way of example. Figure 1 is an elevation of 70 the reel; Figure 2 is an end view thereof with the two winding-up systems or arms in their operative positions; Figure 3 is a similar view with the systems or arms collapsed or in position for removing the skein or 75 skeins from the reel prior to a next winding operation; Figure 4 is a fragmentary cross-section on the line C—D of Figure 5 on an enlarged scale; Figure 5 is a cross-section on the line A—B of Figure 4 with the movable system or arms locked in the position 80 illustrated in Fig. 2; and Figure 6 is a cross-section as in Fig. 5, but with the parts in the position shown in Fig. 3.

In the embodiment shown the reel comprises a rotary shaft A with a system of stationary arms S rigidly attached to said shaft and carrying four bars or rods L in parallel relationship with respect to each other and to the shaft. Movably mounted on the shaft 85 is another system of arms S¹ carrying two bars or rods L¹ only, as usually in reels of 90 the kind in question. The six bars or rods L and L¹ are arranged in such a manner that when they are in operative position, as 95 shown in Fig. 2, they form a regular hexagon. Some of the bars or rods, preferably those of the movable system may be pivotally connected or hinged to the carrying arms 100 in order to facilitate the tilting movement of the arms S¹ for the removal of the skein or skeins. In most cases a single bar or rod L¹ properly hinged to its carrying arm, as shown in Figures 2 and 3, will answer the 105 purpose well.

The construction of a reel as hereinbefore described is old. We shall now proceed to explain our improved locking device with

reference to the drawings, in particular Figures 5 and 6 thereof.

On the inner face of one of the two stationary members S a lug or nose N is provided and on the opposite side or face of the adjacent movable member S^1 a spring F is mounted with sufficient play to allow the said lug N to engage in a seat R formed in the spring by bending the same inwards and outwards. Both the lug and the spring may be made of acid-proof material, preferably of acid-proof steel. In order to prevent the movable system or member S^1 from turning, when pulled back into the operative position, over and beyond the said position shown in Fig. 2, that is to say, to retain the lug N within the seat R , the spring is further bent outwards, as at a , Figs. 5 and 6, to form a stop or abutment for the body of the lug to engage therewith when properly seated in the seat R , as will be readily understood from Fig. 5.

The winding-up operation being finished, the skeins of wet, shrinking yarn are to be removed from the reel and to this end the system or member S^1 is to be turned about the shaft from the position shown in Fig. 2 to the position illustrated in Fig. 3. This may be done by manually forcing one of the two bars or rods L^1 towards the adjacent bar or rod L of the stationary member, as in Fig. 3. As the top of the lug N is rounded or of conical shape fitting snugly into the correspondingly shaped seat R , and the spring readily yields under the forcing action, the lug will be easily disengaged from its seat to allow the member S^1 to be turned into the position shown in Fig. 3. Simultaneously therewith the hinged bar or rod L^1 will tilt over, as shown in Fig. 3, so that the skeins depend loose on the bars or rods and can be readily removed therefrom.

For a subsequent winding-up operation the movable member S^1 is manually returned from the position shown in Fig. 3 into the position shown in Fig. 2, where the spring F , in co-operation with the lug N , acts to lock the member in the operative position.

It is apparent that in carrying out our invention some changes from the construction herein shown and described may be made. We would, therefore, have it understood that we do not limit ourselves thereto, but hold ourselves at liberty to make such departures therefrom as fairly fall within the spirit and scope of our invention.

What we claim is:

1. A yarn reel, comprising a rotatable shaft, a system of fixed arms rigidly attached to said shaft and provided with longitudinal parallel winding bars, a system of movable arms loosely mounted on said shaft

adjacent said fixed arms and so as to be capable of angular movement with respect to said fixed arms, longitudinal parallel winding bars provided on said system of movable arms, a lug or nose provided on one of the stationary arms and a spring yieldingly mounted on one of the loose arms and having a depression or seat for the said lug or nose to engage in, as and for the purpose set forth.

2. A yarn reel, comprising a rotatable shaft, a system of fixed arms rigidly attached to said shaft and provided with longitudinal parallel winding bars, a system of movable arms loosely mounted on said shaft adjacent said fixed arms and so as to be capable of angular movement with respect to said fixed arms, longitudinal parallel winding bars provided on said system of movable arms, a lug or nose provided on one of the stationary arms, a spring yieldingly mounted on one of the loose arms and having a depression or seat for the said lug or nose to engage in, and a stop on said spring contiguous to said seat or depression, as and for the purpose set forth.

3. A yarn reel, comprising a rotatable shaft, a system of fixed arms rigidly attached to said shaft and provided with longitudinal parallel winding bars, a system of movable arms loosely mounted on said shaft adjacent said fixed arms and so as to be capable of angular movement with respect to said fixed arms, longitudinal parallel winding bars provided on said system of movable arms, a lug or nose fixed on one of the fixed arms so as to face the adjacent movable arms, a spring yieldingly mounted on one of the loose arms having a depression or seat for said lug to engage in and an abutting edge formed in the said spring contiguous to the said seat or depression substantially as and for the purpose set forth.

4. A yarn reel, comprising a rotatable shaft, a system of fixed arms rigidly attached to said shaft and provided with longitudinal parallel winding bars, a system of movable arms loosely mounted on said shaft adjacent said fixed arms and so as to be capable of angular movement with respect to said fixed arms, longitudinal parallel winding bars provided on said system of movable arms, a lug or nose made of acid proof material provided on one of the stationary arms and a spring made of acid proof material yieldingly mounted on one of the loose arms and having a depression or seat for the said lug or nose to engage in, as and for the purpose set forth.

In testimony whereof we have signed our names to this specification.

DR. EMIL ELSAESSER.
